JACK

Erich Bloch, New York, N. Y.

Application April 8, 1941, Serial No. 387,441

16 Claims. (Cl. 254—1)

This invention relates primarily to lifting devices and the like. More particularly, the invention relates to a lifting jack having an extensible lifting member composed of successive shaft portions which can be stored compactly, the jack being capable in operation of lifting bodies disposed either close to or a substantial distance above the ground. However, certain features of the invention have broader application as hereinafter described.

Conventional lifting jacks have a limited range of lifting height. If adapted to lift low bodies the conventional jack cannot be used to lift bodies disposed a substantial distance above the ground. If the conventional jack is adapted to lift bodies disposed high off the ground, it cannot be placed under low bodies, and is cumbersome and too heavy to be moved with ease.

There have been suggested heretofore jacks capable of lifting bodies to a considerable height, such jacks being provided with an extensible member composed of successive sections each of which when raised upwardly by a suitable mechanism will lift preceding sections of the extensible member. Lifting jacks of this character generally have been constructed with extensible lifting members composed of solid sections either unconnected or articulated so that the propelling mechanism moves successive solid sections into lifting position. Both the unconnected and the articulated solid sections known heretofore have been subject to the disadvantage that they were not adapted to lift objects located close to the ground or that when used to lift objects located a substantial distance above the ground the extensible lifting member composed of the solid sections have a tendency to buckle and allow the lifted object to fall. Other lifting jacks have been known in which the extensible lifting member is composed of a plurality of solid cylindrical shaft portions, but these cylindrical shaft portions are also subject to a tendency to buckle. The solid sections in lifting jacks known heretofore require a large amount of space for storage of the sections of the extensible lifting member. Thus, lifting jacks adapted to lift objects disposed a substantial distance above the ground have required so much space for storage of the lifting elements as to render such jacks impractical because of their size.

I have devised a novel lifting jack having an extensible lifting member composed of a plurality of sections which are light yet strong and resist buckling and which may be stored in a minimum of space. In accordance with my in-

vention I provide a frame and a plurality of groups of mating sections movably mounted within the frame, each group when mated in juxtaposition forming a relatively short shaft portion adapted to abut at its ends another similar shaft portion formed by another group of mated sections. The shaft portions are preferably hollow and means are provided for storing unmated sections in nesting relationship within the frame. Means are also provided for advancing the mating sections of successive groups into juxtaposition in abutment with the mated sections of the preceding group. Corresponding sections of each group of mating sections are articulated, as by coupling means, in such manner as to permit storage thereof in nesting relationship to one another, the unmated corresponding sections preferably being stored within the frame in a position substantially parallel to the axis of the shaft portion formed by mated sections. Supporting means is mounted on the frame for maintaining the axis of the shaft in fixed position with respect to the frame. Projecting elements secured to each of the mating sections engage guide tracks mounted on the frame adapted, in cooperation with the coupling means, to guide mating sections of successive groups from the storage space into juxtaposition. Driving means is provided engaging mated sections for moving each group of mated sections along the axis of the shaft formed by the mated sections. These and other features of the apparatus of my invention will be seen in the drawings in which:

Fig. 1 is a side view of the lifting jack, partly in section;

Fig. 2 is a plan view taken along line 2—2 in Fig. 1;

Fig. 3 is a cross-sectional detailed view of the coupling means between successive corresponding mating sections when successive mated sections are in abutment as shown at A in Fig. 1 and taken along line 3—3 in Fig. 4;

Fig. 4 is a view of the coupling means shown in Fig. 3 taken along line 4—4 in Fig. 3;

Fig. 5 is a plan view of the coupling means shown in Fig. 3 taken along line 5—5 in Fig. 4;

Fig. 6 is a cross-sectional view of the coupling means when successive corresponding mating sections are in the position indicated at B in Fig. 1;

Fig. 7 is a cross-sectional view of another modification of the lifting jack of this invention;

Fig. 8 shows mating sections particularly adapted for use as an extensible conduit for fluids; and

Figs. 9, 10, 11 and 12 show the cross-sectional

shape of several modified forms of mating sections.

The lifting jack illustrated in Figs. 1 and 2 comprises a suitable frame 13. Mounted within the frame and projecting a relatively short distance above the top thereof is a cylindrical supporting member 14. The supporting member 14 is provided adjacent its upper portion with two or more sets of bearings such, for example, as the bearing supports 16 carrying the ball bearing 16. Each set of bearings may comprise, for example, six bearings disposed radially about the cylindrical supporting member 14 on the outer surface thereof. The two sets of bearings 16 shown in Fig. 1 are disposed longitudinally of the cylindrical supporting member 14 a relatively short distance apart on the upper outer surface thereof.

The uppermost section of the extensible lifting member comprises a cylindrical portion 17 of slightly greater diameter than the diameter of the cylindrical supporting member 14 and adapted to rest, in its lowermost position, about the bearings 16 on the upper portion of the cylindrical supporting member 14. The cylindrical portion 17 is provided at its top end with a cap 18 provided with a recessed seat 20. A projecting member 21 is mounted on a plate 22 adapted to rotate within the recessed seat 20, friction being minimized by ball bearings 23. The projecting member 21 is adapted to engage an appropriate saddle or recess in the body of the object to be raised by the lifting jack.

The mating sections 24 shown in Figs. 1 and 2 comprise vertical half-sections of a relatively short cylinder such that when mated in juxtaposition the mating sections form a relatively short hollow cylindrical shaft portion. The general shape of these mating sections 24 is shown in Fig. 8. The mating sections 24 are stored in nesting relationship within the frame 13, the stored nested sections in accordance with the now preferred embodiment of my invention assuming a position substantially parallel to the axis of the shaft portion formed by mated sections. Corresponding mating sections are stored together within the frame on each side of the cylindrical supporting member 14.

Each of the mating sections is provided adjacent its open side with projections 25 extending outwardly from the mating section substantially at right angles to the axis thereof. The projections 25, which may with advantage be of the roller type, engage the guide tracks 26 on each side of the frame, the guide tracks 26 and the projections 25 being so positioned as to hold the stored mating sections suspended above the bottom of the frame 13. The guide tracks 26 extend longitudinally of the storage space within the frame 13 toward the cylindrical supporting member 14 in a direction perpendicular to the axis of the supporting member 14. The guide tracks 26 curve upwardly in the vicinity of the cylindrical supporting member 14 and converge along each side of the frame 13 substantially parallel with the axis of the cylindrical supporting member 14. Thus, mating sections moved toward the cylindrical supporting member 14, being guided by the projections 25 engaging the guide tracks 26, are guided inwardly and upwardly as they approach the cylindrical supporting member 14 until the projections 25 of each group of mating sections 24 move into the point of convergence of the guide tracks 26. At this point, the

7 mating sections of each group are brought into juxtaposition and form a relatively short hollow shaft portion surrounding the cylindrical supporting member 14. The mated sections thus 5 brought into juxtaposition engage, at their interior surface, the bearings 16. Thus, the cylindrical supporting member 14 supports the mated sections 24 for maintaining the axis of the shaft, 10 composed of one or more abutting shaft portions, in fixed position with respect to the frame 13. The bearings 16 permit vertical and supported movement of the mated sections along the cylindrical supporting member 14 with a minimum of friction.

15 Each of the mating sections 24 is provided on its outer surface diametrically opposite its open face with a slotted channel 27 extending longitudinally thereof. The slotted channel 27 is disposed immediately adjacent the outer surface of each mating section 24 at the lower end thereof. The slotted channel 27 projects outwardly and upwardly towards the upper end of each mating section 24, the slotted channel 27 adjacent the upper end of each mating section being separated 20 from the exterior surface of the mating section and forming the compartment 28. The upper end of each slotted channel 27 projects upwardly beyond the upper end of the mating section 24 to which it is attached in a direction substantially parallel to the axis thereof.

25 Successive corresponding mating sections are interconnected or articulated by a connecting link such as the coupling means 30. This coupling means may with advantage be of the type described in U. S. Patent No. 1,984,092. Such a coupling means comprises two L-shaped arms 31 and 32. Arms 31 and 32 are pivoted on a common axis 33 in the bend of each L. The end of the long leg of L-shaped arm 31 is slidably mounted in a groove 34 in the sliding member 35. The sliding member 35 is positioned within the slotted channel 27 and is provided with rounded sides to permit pivotal as well as sliding movement of the sliding member 35 within the slotted channel 27. The sliding member 35 is held within the slotted channel 27 by means of the shoulder 36 in the lower end of the channel. The end of the short leg of the L-shaped arm 31 is pivotally mounted as at 37 in the pivoted member 38. The pivoted member 38 is mounted for rotation about the fixed axis 39 supported by the base member 40, the outer surface of the pivoted member 38 being curved as at 41 to permit pivoting of the member 38 about the axis 39 within the chamber 28. The base member 40 is mounted on the upper exterior surface of the mating section 24. The end of the long leg of the L-shaped arm 32 is slidably mounted in the groove 42 in the pivoted member 38. The 45 end of the short leg of the L-shaped arm 32 is pivotally mounted as at 43 in the sliding member 35. The coupling means advantageously 50 comprises, as shown in the drawings, a pair of the L-shaped arms 31 and a pair of the L-shaped arms 32 in order to impart additional strength and rigidity to the coupling means. However, the specific coupling means has been described hereinabove merely by way of example and the invention is not limited thereto. Thus, other coupling means of similar or equivalent functions may be used in lieu of the specific coupling means described hereinabove in accordance with my invention.

55 The function of the above-described coupling means is such as to permit horizontal displace-

ment of succeeding corresponding mating sections 24 and to effect abutment of the ends of these succeeding corresponding mating sections 24 when the succeeding mating sections are brought into vertical alignment, as shown in Fig. 3 (the position shown at A in Fig. 1). This type of coupling means, together with the feature of the coupling means, being slidably mounted in the slotted channel 21, permits storing the corresponding sections of each group of mating sections in nested relationship within the frame 13. Thus, the corresponding mating sections 24 stored in nesting relationship within the frame 13 are articulated by the coupling means comprising the pivoted member 38 pivotally mounted within the chamber 28 and the sliding member 35 disposed within the upper portion of the slotted channel 21. As each mating section is advanced toward the cylindrical supporting member 14 along guide tracks 26 the mating section 24 is raised vertically as its projections 25 move along the upwardly curved portion of the guide track 26, and the sliding member 35 of the coupling means slides downwardly along the slotted channel 21 of the mating section 24 being raised. When the mating section 24 is thus brought into juxtaposition, by means of guide tracks 26, with its complementary mating section, the action of the coupling means is such as to draw the mating sections 24 of this group upwardly into abutment with the preceding group of mated sections as shown at A in Fig. 1. The reverse of this procedure takes place and the mating sections are returned to their storage space as the extensible lifting member is lowered by reversal of the driving mechanism.

The upper ends of the slotted channels 27 of the mated sections of each group overlap the bottom portion of the slotted channel 27 of the preceding group of mated sections thus holding together the mated sections of the preceding group. This construction contributes to the non-buckling characteristic of the extensible lifting member of my invention. At all times the lowermost group of mated sections will be held in juxtaposition by the terminating, vertically disposed, converging ends of the guide tracks 26, and the axis of the shaft composed of successive abutting groups of mated sections is held in fixed position with respect to the frame 13 by means of the support given to the lowermost mated group by the cylindrical supporting member 14.

Each mating section 24 is provided on each side with a tooth rack 44 extending substantially the full length of the mating section as shown in Fig. 8. Mated sections supported by the cylindrical supporting member 14 are raised, as shown in Fig. 2, by means of pinions 45 engaging the tooth racks 43. The pinions 45 are driven, for example, by means of additional pinions 46 mounted on shafts 47 driven by a common drive chain 48, one of these shafts 47 being driven by a power chain 49. It must be understood, however, that other equivalent driving mechanism may be used within the scope of my invention. Thus, in the specific driving mechanism shown in Fig. 2, by driving the chain 49 the pinions 45 which engage the tooth racks 44 raise the mated sections 24 upwardly around the cylindrical supporting member 14. As the mated sections are being raised succeeding mating sections are drawn upwardly from the storage space within the frame 13 into abutment with the preceding mated sections.

The modified lifting jack shown in Fig. 7 differs

75

from that shown in Figs. 1 and 2 in the lifting mechanism. In the apparatus shown in Fig. 7, a stationary mandrel 50 is positioned centrally within the frame 13 in the position corresponding to the cylindrical supporting member 14 shown in Figs. 1 and 2. A concentric rotatable shaft in the form of the cylinder 51 surrounds the mandrel 50 and is separated therefrom by the bearings 52 mounted in suitable bearing supports 53. The lower portion of the rotatable cylinder 51 terminates in an annular bevel gear 54 which is supported on frame 13 by means of ball bearings, or the like, 55. The cylinder 51 is rotated by rotary movement of the bevel gear 56 engaging the bevel gear 54. The upper outer surface of the cylinder 51 is provided with a helical tooth 57 which may with advantage comprise one complete helical revolution about the cylinder 51. The ends of this tooth are preferably tapered as at 58. The inner surface of the mating sections 24 is provided with a helical groove 60 having the same pitch as the helical tooth 57. By selecting a pitch of the groove 60 which is either equal to or a fraction of the length of the mating sections 24, each mating section may be provided with the same groove so that such mating sections are standardized and therefore interchangeable. Rotary movement of the cylinder 51 in the direction of the arrow raises the mated sections to afford the desired lifting action. The mating sections 24 raised vertically and brought into juxtaposition by the projections 25 moving along the upwardly converging guide tracks 26 form a cylinder having internal grooves 60 which are engaged by the tooth 57. The tapered ends of the tooth 57 accommodate slight variations from a perfectly continuous helical groove 60 occasioned, for example, by a slight gap between the ends of the already mated sections and the immediately succeeding mating sections being brought into juxtaposition.

The mating sections shown in Fig. 8, although of the general form used in accordance with the modification of my lifting jack shown in Figs. 1 and 2, are modified by being provided with a cut-out portion 61 adjacent the upper inner surface thereof and with a cut-away portion 62 on the lower exterior surface thereof. This modification permits operative and fluid-tight engagement between the adjoining ends of succeeding mated sections and is particularly advantageous when the extensible member of my apparatus is used for conveying fluids. A fluid-tight joint is further provided between mated sections in juxtaposition by engagement between the tongues 63 and the grooves 64 provided in the longitudinal edges of the mating sections along their open faces.

Although my invention has been described hereinabove with respect to the use of mating half-sections which form the hollow shaft portions of the extensible lifting member, other types of shaft portions may be used with advantage. For example, the mating sections when mated may have a cross-sectional configuration which is pear-shaped, as shown in Fig. 9, or an elliptical shape such as is shown in Fig. 10, a rectangular shape as shown in Fig. 11, or a polygonal shape as shown in Fig. 12. The shaft portions used in accordance with my invention may be half-sections of the desired shape as described hereinabove, or they may comprise a plurality of mating sections such that three or more mating sections together form a single shaft portion.

It will be seen, therefore, that the apparatus

of my invention presents a lifting jack which is capable of lifting bodies located close to the ground or bodies disposed high above the ground. The lifting jack of my invention is further characterized by a large lifting range, it being equally effective when lifting low bodies as when lifting high bodies. Moreover, the extensible lifting member is strong, durable and light yet resists the tendency for the sections of the extensible lifting member to buckle. The lifting jack is compact, and the nesting relationship between stored mating sections which form the extensible lifting member permits the inclusion of a large number of these mating sections within the frame of the jack. Inasmuch as the groups of mating sections may form hollow shaft portions, which shaft portions may be such as to be fluid-tight, the extensible shaft in accordance with the invention may be utilized not only as a lifting member but also, with particular advantage, as an extensible fluid-conducting member.

Thus, although the apparatus of my invention has been described with particular reference to lifting jacks wherein the invention presents outstanding advantages of particular importance in the construction, operation and use of such lifting jacks, it must be understood that the invention is not limited thereto but is applicable more broadly to apparatus wherein an extensible tube or shaft is desired.

I claim:

1. In apparatus of the character described, a frame, a plurality of groups of mating sections movably mounted within said frame, each group when mated in juxtaposition forming a relatively short hollow shaft portion adapted to abut at its ends another similar shaft portion formed by another group of mated sections, means for storing unmated sections in nesting relationship within said frame, and means for advancing said sections of successive groups into juxtaposition in abutment with the mated sections of the preceding group.

2. In apparatus of the character described, a frame, a plurality of groups of mating sections movably mounted within said frame, each group when mated in juxtaposition forming a relatively short shaft portion adapted to abut at its ends another similar shaft portion formed by another group of mated sections, means for storing the sections within said frame in a position substantially parallel to the axis of the shaft portion formed by mated sections, and means for advancing said sections of successive groups into juxtaposition in abutment with the mated sections of the preceding group.

3. In apparatus of the character described, a frame, a plurality of groups of mating sections movably mounted within said frame, each group when mated in juxtaposition forming a relatively short hollow shaft portion adapted to abut at its ends similar shaft portions formed by similar groups of mated sections, means for storing said sections in nesting relationship within said frame in a position substantially parallel to the axis of the shaft portion formed by mated sections, and means for advancing unmated sections of successive groups into juxtaposition in abutment with the mated sections of the preceding group.

4. In apparatus of the character described, a frame, a plurality of groups of mating sections movably mounted within said frame, each group when mated in juxtaposition forming a relatively short hollow shaft portion adapted at its ends to

abut similar shaft portions formed by similar groups of mated sections, coupling means interconnecting successive corresponding sections of said groups, means for storing corresponding sections of said groups in nesting relationship within said frame, supporting means mounted on the frame for maintaining the axis of the shaft in fixed position with respect to the frame, and means for advancing unmated sections of successive groups into juxtaposition in abutment with the mated sections of the preceding group.

5. A lifting jack which comprises a frame, a plurality of groups of mating sections movably mounted within said frame, each group when mated in juxtaposition forming a relatively short hollow shaft portion adapted at its ends to abut similar shaft portions formed by similar groups of mated sections, means for storing corresponding sections of said groups in nesting relationship within said frame, means for guiding said mating sections from the storage means into juxtaposition in abutment with the mated sections of the preceding group, supporting means mounted on the frame for maintaining the axis of the shaft in fixed position with respect to the frame, and driving means engaging said mated sections for moving the mated sections along the axis of the shaft formed by said sections.

6. In apparatus of the character described, a frame, a plurality of groups of mating sections movably mounted in said frame, each group when mated in juxtaposition forming a relatively short hollow shaft portion adapted at its ends to abut similar shaft portions formed by similar groups of mated sections, corresponding sections of said groups being articulated in such manner as to permit storage thereof in nesting relationship to one another, means for guiding said sections from the storage means into juxtaposition, and means for moving said sections into juxtaposition in abutment with the mated sections of the preceding group.

7. In apparatus of the character described, a frame, a plurality of groups of mating sections movably mounted within said frame, each group when mated in juxtaposition forming a relatively short hollow shaft portion, said sections being provided at the ends thereof with means for operatively engaging the ends of adjoining corresponding sections, supporting means mounted substantially centrally within the frame for maintaining the axis of the shaft in fixed position with respect to the frame, means for storing corresponding sections of said groups in nesting relationship separately within the frame on opposite sides of said supporting means, and means for advancing said sections of successive groups from the storage means into juxtaposition in abutment with the mated sections of the preceding group.

8. A lifting jack which comprises a frame, a plurality of groups of mating sections movably mounted in said frame, each group when mated in juxtaposition forming a relatively short hollow shaft portion adapted at its ends to abut similar shaft portions formed by similar groups of mated sections, coupling means interconnecting successive corresponding sections of said groups, means for storing said sections within the frame in nesting relationship, guide tracks mounted on the frame adapted in cooperation with said coupling means to guide mating sections of said groups from the storage means into juxtaposition, projecting elements secured to said mating sections and engaging the guide tracks,

supporting means mounted on the frame for maintaining the axis of the shaft in fixed position with respect to the frame, and driving means engaging the mated sections for moving the sections of said groups along the axis of the shaft formed by said mated sections.

9. A lifting jack which comprises a frame, a plurality of groups of mating sections movably mounted in said frame, each group when mated in juxtaposition forming a relatively short shaft portion adapted at its ends to abut similar shaft portions formed by similar groups of mated sections, coupling means interconnecting successive corresponding sections of said groups, the coupling means being adapted to draw the corresponding mating section of one group into abutment with the preceding corresponding section as said mating section is brought into juxtaposition with the other mating section of its group, means for storing the mating sections within the frame in a position substantially parallel to the axis of the shaft portion formed by mated sections, guide tracks mounted on the frame adapted in cooperation with said coupling means to guide mating sections of said groups from the storage means into juxtaposition, projecting elements secured to said mating sections and engaging the guide tracks, supporting means mounted on the frame for maintaining the axis of the shaft in fixed position with respect to the frame, and driving means engaging the mated sections for moving the sections of said groups along the axis of the shaft formed by said mated sections.

10. A lifting jack which comprises a frame, a plurality of groups of mating sections, each group comprising a pair of vertical half-sections of a relatively short cylinder movably mounted within the frame, each pair of half-sections when mated in juxtaposition forming a relatively short hollow shaft portion adapted to abut at its ends another similar shaft portion formed by mated half-sections of similar groups, a slotted channel extending along the length of the exterior surface of each mating section; a connecting link slidably mounted at one end thereof in the slotted channel and connected at the other end thereof with one end of the next succeeding corresponding section, whereby movement of one section is imparted to the next succeeding corresponding section and whereby the corresponding sections may be stored in nesting relationship, means for storing corresponding unmated sections in nesting relationship within said frame, and means for advancing said sections of successive groups into juxtaposition in abutment with the mated sections of the preceding group.

11. In combination with successive corresponding sections of a plurality of groups of mating sections interconnected so as to impart the motion of one section to the next succeeding corresponding section, each group of sections when mated in juxtaposition forming a relatively short shaft portion, a slotted channel extending along the length of each mating section and a connecting link slidably mounted at one end thereof in the slotted channel and connected at the other end thereof with one end of the next succeeding corresponding mating section.

12. A lifting jack which comprises a frame, a plurality of groups of mating sections movably mounted within said frame, each group when mated in juxtaposition forming a relatively short hollow shaft portion adapted to abut at its ends another similar shaft portion formed by another

group of mated sections, a rack attached to the surface of each section and disposed along the length thereof, a pinion operatively engaging the racks of said sections when mated in juxtaposition, means for storing unmated corresponding sections of said groups in nesting relationship, and means for advancing said sections successively into juxtaposition.

13. A lifting jack which comprises a frame, a plurality of groups of mating sections movably mounted within said frame, each group when mated in juxtaposition forming a relatively short hollow shaft portion adapted to abut at its ends another similar shaft portion formed by another group of mated sections, said mating sections being provided with helical elements, driving means rotatable about the axis of the shaft portion formed by a group of said mating sections when brought into juxtaposition and having helical elements adapted to engage the helical elements on said mating sections, means for storing unmated corresponding sections of said groups in nesting relationship, and means for advancing said sections successively into juxtaposition.

14. A lifting jack which comprises a frame, a plurality of groups of mating sections movably mounted within said frame, each group when mated in juxtaposition forming a relatively short hollow shaft portion formed by another group of mated sections, said mating sections being provided on the interior surface thereof with a helical groove, a rotatable shaft mounted for rotation within the hollow shaft portion formed by a group of said mating sections when brought into juxtaposition, said shaft being provided with a helical tooth adapted to engage the helical groove on the interior surface of said mating sections when brought into juxtaposition, means for storing unmated corresponding sections of said groups in nesting relationship, and means for advancing said sections successively into juxtaposition.

15. A lifting jack which comprises a frame, a plurality of groups of mating sections movably mounted within said frame, each group when mated in juxtaposition forming a relatively short hollow shaft portion, a slotted channel extending along the length of the exterior surface of each mating section, a connecting link slidably mounted at one end thereof in the slotted channel and connected at the other end thereof with one end of the next succeeding corresponding mating section, whereby movement of one section is imparted to the next succeeding corresponding section and whereby the corresponding sections may be stored in nesting relationship, means for storing corresponding sections within the frame in nesting relationship, guide tracks mounted on the frame, projecting elements secured to said mating sections adapted to engage the guide tracks, the projecting elements and the guide tracks being adapted in cooperation with the connecting links between corresponding mating sections to guide the mating sections of said groups from the storage means into juxtaposition, supporting means mounted substantially centrally within the frame for maintaining the axis of the shaft in fixed position with respect to the frame, and driving means engaging the mated sections for moving the sections of said groups along the axis of the shaft formed by said mated sections.

16. In apparatus of the character described, a frame, a plurality of groups of mating sections movably mounted in said frame, each group

when mated in juxtaposition forming a relatively short hollow shaft portion adapted at its ends to abut similar shaft portions formed by similar groups of mated sections, means for storing the corresponding sections within separate portions of the frame in nesting relationship, supporting means mounted within the frame substantially intermediate the separate storing means for said corresponding sections for maintaining the axis of the shaft in fixed position with respect to the frame, coupling means interconnecting successive corresponding sections of said groups, guide

5 tracks mounted on the frame extending from the storage means inwardly toward the supporting means in a direction perpendicular to the axis of the shaft portions formed by said mated sections, said guide tracks curving in the vicinity of said supporting means and converging parallel to the axis of the shaft portions, projecting elements secured to said mating sections and engaging the guide tracks, and means for moving each 10 group of mating sections successively along the guide tracks and into juxtaposition.

ERICH BLOCH.
